ARTHUR G. BAGNALL AND JAMES A. TAYLOR, OF CLEVELAND, OHIO.

COMBINED PLASTER AND CEMENT BASE-SCREED.

1,110,369.

Specification of Letters Patent. Patented Sept. 15, 1914.

Application filed February 28, 1914. Serial No. 821,649.

To all whom it may concern:

Be it known that we, ARTHUR G. BAGNALL and JAMES A. TAYLOR, citizens of the United States, residing at Cleveland, in the county 5 of Cuyahoga and State of Ohio, have invented a certain new and useful Improvement in Combined Plaster and Cement Base-Screeds, of which the following is a full, clear, and exact description, reference being, 10 had to the accompanying drawings.

This invention relates to cement and plaster working and has for its object the provision of a metal device which may be applied permanently to a wall or partition to, 15 form a base for the wall plaster, and also, form a screed or guide for the purpose of steadyng a molding tool, and in addition may separate the plaster wall from the cement base while keeping both of those materials firmly in place. At the present time, 20 in the construction of fire proof buildings such as offices, lofts, and the like, it is becoming increasingly common to form the floor of concrete, which concrete is carried up around the base of the walls for a short 25 distance in place of the usual base board, the joint between this concrete base and the concrete floor being made rounding so as to form a kind of sanitary base cove. In the 30 process of finishing the interior of the room it has first been customary to affix to the wall at a point adjacent to the floor a wooden ground to which the plaster coat is drawn. After this plaster has been laid and hardened, 35 said ground is removed, and a second wooden strip is tacked to the face of the plaster just above its lower edge, this second strip being employed as a screed for guiding the molding tool whereby the base 40 is formed. After the laying of the floor and the molding of the base, this second wood strip has no further use, and is therefore torn away, leaving the plaster of the wall and the cement of the base in close 45 juxtaposition. Also, as will be obvious, the tearing away of these two wooden members is certain to do considerable damage to the plaster of the wall which has, therefore, to be repaired by the usual slow method of 50 patching, and even then it is impossible to restore the wall to the desired smooth condition. In addition it is a well known fact that when plaster and Portland cement concrete are laid against each other a chemical 55 action frequently occurs which becomes very

destructive to one or the other of the materials, and with the process above described it is very difficult to maintain these materials out of contact at all points.

Accordingly it is the object of our invention to provide a single member which shall both form a ground for the plaster and a screed for the cement base, which shall be left permanently in the wall, and which shall keep the plaster and the cement firmly 60 in place while maintaining them sufficiently apart to minimize the danger of chemical reaction.

In the drawings accompanying and forming a part of this application we have illustrated one form of device whereby all of these objects may be attained, the same being the preferable embodiment of our invention so far as we have hitherto conceived the same, though it is obvious that other 75 specific constructions could be employed to the same end.

In these drawings Figure 1 is a perspective view of a portion of a metal plaster and cement base screed constructed in accordance with our invention; Fig. 2 is a vertical; cross-sectional view of a portion of a wall showing the same in place; Fig. 3 is a base view of a portion of one end of such metal screed; and Fig. 4 is a cross-sectional 85 view of the screed alone, showing its adaptability to walls of different thickness.

Describing the drawings by reference to the numerals placed thereon, 1 represents the original floor or sub-floor which may be 90 of interlocking tile, concrete, or any other suitable material and construction, and 2 represents a portion of a wall, here shown as formed of hollow tile and having mortar joints 3. 4 represents the finish floor, also 95 of concrete, 5 the concrete base, forming a continuation of the floor and extending up the wall the customary or any suitable distance, 6 the fillet or rounded corner between the floor and base, and 7 the wall plaster, 100 which is applied to the face of the tile in the usual or any suitable manner.

Our improved metal base screed is constructed of a single piece of sheet metal, bent to the required form by the usual metal 105 bending methods, and is applied to the wall before either the plaster or the cement is put in place. This screed, in its preferred embodiment, comprises a pair of flat elongated webs 10 and 11 making an oblique 110

angle with each other and having at their adjacent edges the parallel outwardly extending flanges 12 and 13 respectively. The width of the flange 13 is greater than that of the flange 12 and at its margin the metal is folded abruptly so as to form a ledge portion 14 lying flat against the face of said flange 13, and the edge of this folded portion is bent at substantially right angles thereto to form the wall 15 which merges with the outer edge of the flange 12. The web 10 is formed with a plurality of spaced apertures 16-16 which preferably extend through the flange 12 as indicated at 17, and the web 11 is formed with other apertures 18-18 which are preferably located out of line with the apertures 16 for a purpose hereafter described. Also the outer edges of the webs 10 and 11 are formed with securing lips 20-20 formed at frequent intervals with perforations 21 for the reception of nails 22 or other suitable securing means.

In use these metal screeds are cut to any suitable length and applied to the face of the wall at the requisite height, being secured in place by means of nails driven into the mortar bonds between adjacent bricks or tiles. In case one of the flanges 20-20 shall coincide with a horizontal bond as shown in Fig. 2, the nails can be inserted anywhere. In case the bonds shall not be of the right height, the closeness together of the apertures 21-21 will cause some apertures to coincide with nearly every vertical joint, at least sufficient for the purpose of holding this screed in place. The plaster is applied in the usual manner, to the level of the wall portion 15 as illustrated in Fig. 2, some of the material entering through the perforations 16-16 so as to become keyed therein as illustrated in Fig. 2. The upper face of the flange 13 will arrest the falling movement of these keys and prevent the plaster from falling to the space used for the cement.

After the plaster has hardened the floor is laid in the usual manner, and additional cement packed into the corner beneath the screed sufficient for the purpose of forming the cement base. It is then compressed and shaped by means of a suitable molding tool which is run horizontally around the room, the ledge 14 being employed to guide and steady the tool. The cement will enter the perforations 18-18 and become keyed therein as illustrated at 25, but with very little danger of coming into contact with the plaster by reason of the offsetting of the perforations 16 and 18. It will be noted that the ledge 14 and wall 15 of the screed are left exposed, thus forming a metal angle which strengthens the construction very materially at this point and prevents chipping or cracking the concrete base by contact with furni-

ture and the like. Also this construction permits the use of a base molding at this point if desired, and avoids the necessity of removing any screeds, grounds, or the like, thus avoiding the necessity of breaking the 70 finish and later patching the same. The arrangement here described also permits the same screed to be used with plasters of different thickness, since to adapt this screed to plasters of different thickness it is necessary 75 merely to bend the same in or out as shown in full-and-dotted lines in Fig. 4.

It will be seen that we have produced a device of great simplicity, utility, and reliability, although it may obviously be changed 80 in many particulars without departing from the scope of our invention.

Having thus described our invention, what we claim is:-

1. A plaster and cement base screed for 85 walls, consisting of a pair of converging webs, outwardly extending flanges at the adjacent margins of said webs, a wall portion at the margin of one of said flanges and adapted to lie in the plane of the plaster, a 90 fold integral with the edge of the other web and adapted to overlie the top of the cement base, said fold being integral with the edge of said wall portion, and means to secure said webs to a wall. 95

2. A plaster and cement base screed for 100 walls formed from a single piece of sheet metal and comprising a pair of converging apertured webs having perforated securing lips at their outer edges and also having at 105 their adjacent edges a pair of outwardly extending flanges of different widths, the outer margin of one flange extending from the plane of said lips to a distance equal to the thickness of the plaster coat and the other to a distance equal to the thickness of the cement base, and the outer margins of said flanges being connected by integral portions adapted to form the angle between the 110 plaster and base. 110

3. A plaster and cement base screed for 115 walls, formed from sheet metal and comprising a pair of converging apertured webs having securing portions at their outer edges and forwardly extending flanges at their adjacent edges, one of said flanges having a 120 wall portion defining the thickness of the plaster and the other flange having a straight edge defining the top of the cement base, said wall portion and said straight edge portion being integrally connected and the apertures in one web being staggered with respect to those in the other web so as to maintain the plaster and cement keys out of contact with each other. 125

4. A plaster and cement base screed for 130 walls, formed from sheet metal and comprising a pair of converging apertured webs having securing portions at their outer edges and forwardly extending substantially par-

allel flanges at their adjacent edges, one of
said flanges having a wall portion defining
the thickness of the plaster and the other
flange having a greater width than said first
5 flange and connected thereto by an integral
angular portion adapted to guide a molding
tool.

In testimony whereof, we hereunto affix

our signatures in the presence of two wit-
nesses.
